UNITED STATES PATENT OFFICE.

EMMA J. LAWRENCE, OF PHILADELPHIA, PENNSYLVANIA, ASSIGNOR TO
THE HARTLEY CARPET AND RUG COMPANY, OF SAME PLACE.

DESIGN FOR A RUG.

SPECIFICATION forming part of Design No. 16,891, dated September 7, 1886.

Application filed July 8, 1886. Serial No. 207,521. Term of patent 31 years.

To all whom it may concern:

Be it known that I, EMMA J. LAWRENCE, a citizen of the United States, residing in Philadelphia, Pennsylvania, have invented a new and original Design for a Rug, of which the following is a specification.

My design for a rug is represented in the accompanying photographic illustration, which shows one half of the rug, the other half of the rug being merely a duplicate of that shown.

My design comprises a rectangular center piece, A, having a ground color contrasting with the ground color of the border B, and at each end the center piece has an enlarged or widened extension, D. There is also a narrow ribbon-like division-line, E, between the center and border, and preferably, also, between the center and its widened extension. On the ground of the rectangular center are conventional flowers *a* and leaves *a'*, while in the widened extension D is a closer cluster of

leaves and flowers or blossoms of different varieties. Along the margin of the border, outside the division-line and between the widened extension, are conventional ornaments *b b'*, alternating.

I claim—

The herein-described design for a rug, comprising a flowered center piece having rectangular widened extensions at its ends, a border having conventional ornaments, and having a ribbon-like division between the center, its extensions, and border, all substantially as shown and set forth.

In testimony whereof I have signed my name to this specification in the presence of two subscribing witnesses.

EMMA J. LAWRENCE.
